UNITED STATES PATENT OFFICE.

ALEX MOSQUIT, OF CLAYTON, NEW JERSEY.

VENTILATED SHOE.

Application filed October 8, 1928. Serial No. 311,200.

The present invention is directed to improvements in ventilated shoes.

The primary object of the invention is to provide an article of this character so constructed that air will be admitted to the interior of the shoe to maintain the foot in a thoroughly ventilated and cool condition.

Another object of the invention is to provide an article of this nature so constructed that the addition of the ventilating system will in no way detract from the appearance of the shoe.

Another object of the invention is to provide an article of this kind so constructed that air may freely enter the shoe, but dust and grit will be prevented from entering the ventilating medium.

With these and other objects in view, this invention resides in the novel features of construction, formation, combination and arrangement of parts to be hereinafter more fully described, claimed and illustrated in the accompanying drawing, in which:

Figure 1 is a side elevation of a shoe showing the same equipped with a ventilating device.

Figure 2 is a sectional view on line 2—2 of Figure 1.

Figure 3 is a sectional view on line 3—3 of Figure 1.

Referring to the drawing, 1 designates a shoe, in this instance of the low cut type, but it will be of course understood that the invention is applicable to high shoes and boots.

The vamp 2 of the shoe consists of an upper section 3 which is of such width that the longitudinal edges thereof are spaced from the sides of the sole 4, the rear edges of said section being secured to the heel and instep portion of the shoe by lines of stitches 5.

The forward edge of the section 3 is secured to toe section 6 by stitches 7. The vamp further includes side sections 8—8, the rear edges of which are secured by the lines of stitches 5, while the forward edges thereof are se-

cured by the stitches 7, the lower edges of said sections being suitably secured to the sole 4, as at 9. The sections 8—8 are of such width as to lie under or be overlapped by the lower edges of the section 3, the overlapped portions 50 being unsecured for a major distance of their length in order that air can pass freely therebetween.

The fabric lining 10 is secured interiorly of the shoe as is customary and extends across the overlapped portions of the section 3 and sections 8—8, thus preventing the entrance of dirt and grit to the interior of the shoe.

Obviously when the shoe bends during walking the overlapped portion of the sections will move relatively, and due to slight suction created by the bending of the shoe, air will be drawn thereinto and will maintain the interior of the shoe in a cool and ventilated condition.

To prevent distortion of the overlapped portion of the section 3 and sections 8—8, the same are stitched together, as at 11. In this manner the respective sections are unsecured for a major distance of their length.

From the foregoing, it is thought that the construction, operation and many advantages of the herein described invention will be apparent to those skilled in the art, without further description, and it will be understood that various changes in the size, shape and proportion and minor details of construction, may be resorted to without departing from the spirit or sacrificing any of the advantages of the invention.

What is claimed is:

A shoe of the class described, comprising a vamp, said vamp consisting of an upper section, and side sections, the side sections being overlapped by the upper section and unsecured thereto for a major distance of their length to permit free passage of air between the overlapped portions.

In testimony whereof I affix my signature.

ALEX MOSQUIT. [L. s.]
